UNITED STATES PATENT OFFICE.

LEOPOLD M. REBEL, OF PARIS, FRANCE, ASSIGNOR TO ISABEY-PARIS INCORPORATED,
A CORPORATION OF DELAWARE.

DESIGN FOR A POWDER BOX.

Application filed March 9, 1929. Serial No. 30,402. Term of patent 14 years.

To all whom it may concern:

Be it known that I, LEOPOLD M. REBEL, a citizen of the Republic of France, residing at Paris, France, have invented a new, original, and ornamental Design for Powder Box, of which the following is a specification, reference being had to the accompanying drawing, forming a part thereof.

In the drawing,

Fig. 1 is a perspective view of a powder box showing my new design;

Fig. 2 is a top view thereof, and

Fig. 3 is a side view thereof.

I claim:

The ornamental design for a powder box substantially as shown.

LEOPOLD M. REBEL.
